UNITED STATES PATENT OFFICE.

LOUIS G. BOSTEDO, OF ATLANTIC, IOWA, AND HORATIO THOMAS, OF CHICAGO, ILLINOIS, ASSIGNORS TO THE BOSTEDO PACKAGE AND CASH CARRIER COMPANY, OF ATLANTIC, IOWA.

CASH AND PACKAGE CARRIER.

SPECIFICATION forming part of Letters Patent No. 367,951, dated August 9, 1887.

Application filed November 5, 1886. Serial No. 218,080. (No model.)

To all whom it may concern:

Be it known that we, LOUIS G. BOSTEDO, of Atlantic, in the county of Cass and State of Iowa, and HORATIO THOMAS, of Chicago, in the county of Cook and State of Illinois, have invented certain new and useful Improvements in Cash and Package Carriers; and we do hereby declare the following to be a full, clear, and exact description of the invention, so such as will enable others skilled in the art to which it appertains to make and use the same.

Our invention relates to elevators for cash or package carriers.

15 The object of our invention is to provide a means for the automatic disengagement of the elevator when in line with a main track and permit the gradual descent of the elevator a limited distance with the car on it, making 20 the main track continuous, and at the same time to permit the passage of other cars.

A further object is to provide a simple and effective means to cushion or check the fall of the elevator-frame with a car on it when this 25 car by its momentum unlocks the elevator from its engaged alignment with a main lower track and automatically arrest the elevator at a predetermined point.

A further object is to provide a means by 30 which the disengagement of the suspended elevator and car and its continued descent to the hand of the operator may be effected.

A further object is to provide an improved 35 means for automatically arresting cars on the main lower track when the track is opened by a descending car at its station.

With these ends in view our invention consists in certain features of construction and combinations of parts, that will hereinafter be 40 described, and pointed out in the claims.

Referring to the drawings, making a part of 45 this specification, Figure 1 is a front elevation of the elevator in connection with a track system. Fig. 2 is a sectional view of the elevator with the track-section in position with a lower main track. Fig. 3 is a front view of the elevator-track section, showing the car-buffer and track-releaser in position on same. Fig. 4 is a rear view of the elevator-track section, showing the relative position of the latch-

ing-bar on it. Fig. 5 is a rear view of the main lower track at a station with the elevator-track section in position. Fig. 6 is a longitudinal section of Fig. 3. Fig. 7 is a detached view of the cross-head and its latch in section through longitudinal center. Fig. 8 is a section of the air-chamber or dash-pot. Fig. 9 is a side and end view of the cash car or basket.

This improvement is intended to be used, 60 preferably, in connection with the cash and package carrier systems that are the inventions of Louis G. Bostedo, filed August 2, 1886, Serial No. 209,781, and Horatio Thomas, filed August 27, 1886, Serial No. 212,010, although 65 we do not restrict its use to these particular plans, as it can be applied to modifications of these two track systems.

In the systems for cash or bundle carrying above mentioned the main elements are a dispatching and return track that lie in the same vertical plane, the upper track being preferably made the sending-track from clerks' stations and the lower rail the change or package carrying track from the bundle-table or cashier to the clerks' stations. These tracks are sufficiently far apart to permit the free travel 75 of suspended rolling cars or baskets on the upper track, so that no interference will be had with similar transporting-vehicles on the 80 lower track.

Stations are made at proper intervals, and at each station are affixed vertical guide-rods E, that are parallel to each other. These guides are placed a suitable distance from the 85 main-track lines U P. Portions of these tracks are removed, and a rectangular well-hole is formed at each of these points by the rigid attachment of rectangular frames R I', that hold the detached ends of the several tracks in 90 alignment. These frames are secured permanently to the upright guide-rods E E, before mentioned.

Movable track-sections G H are provided to fill the spaces left open at stations. The 95 upper track-section, H, is pivoted by lateral arms at the rear of the rectangular opening or well-hole R, so that it can swing upward if lifted by pressure on its lower edge. The lower track-section, G, rests in normal posi- 100

tion upon lateral projections on the near surfaces of the rectangular frame I', that prevent it from falling below the top surface of main lower track, U.

5 The car-elevator shown in the systems to which our improvement is an adjunct consists of a light frame, S, (see Fig. 1,) having four cylindrical shells or boxes constructed to slide upon the vertical guide-bars E. Upon the 10 face of the frame S is attached a pivoted rocking piece, K², having two lateral arms that carry a horizontal track-section, M, on their outer ends. These arms are of a length to permit this track-piece to register with the main 15 tracks when the elevator-frame S is brought into proper position. Another bar, L, is affixed to the same face of the frame S upon the arms that project a proper length to sustain the bar L parallel to the track-section and in 20 the same vertical plane. It has proper clearance space above the track, and is provided with two dowels that enter sockets in the track-section G (see Fig. 1) when the elevator-frame S is raised sufficiently. The elevator is hoisted 25 or lowered by a chain or cord, C, supported upon grooved pulleys located above the upper track and reaching down to the head of the operator.

In the systems just described the elevator 30 S and its attached track-sections are sustained in connection with the lower main track to receive a returning car by latch-bolts that slide under the track-section at its ends and are retained there by springs. To lower the 35 car these bolts have to be withdrawn by pulling a cord. In this plan of construction switches have to be constructed to shunt a car from another station around the car on the track that may be waiting for the attention of 40 the clerk. Our present invention is designed to obviate this disadvantage and permit a cash-carrying car on reaching its station to instantly and automatically by its momentum disengage the lock that holds the elevator in connection with the lower track, and permit it, 45 with the loaded car, to drop a short distance below the main-track level, and at the same time restore the free track-piece G to its normal position in the track, so that cars for other 50 stations are permitted to pass this station, and the loaded car thus sustained may await the convenience of the clerk to attend to its further depression and removal of the contents. To accomplish this desideratum two vertical 55 guide-bars, a, (see Fig. 1,) are erected. These are centrally affixed to the lower brace or cross-piece, o, of the main guide-rods E, and extend to connect to the outer bar, N, of the frame I' of the lower track, U. Upon the 60 shorter guide-bars, a, is placed in sliding connection the cross-head b. This is shown in Figs. 1, 2, and 7. It is preferably made of a rectangular form, with perforated bosses d on its side edges, that are designed to receive the guides a and slide up and down thereon. 65 At a point midway between these bosses d a slot is cut vertically to receive the latching-

70 bracket c. This is sustained by a pivot-connection at e, and it has a lateral limb, h, made to project rearwardly to form a lever by which 75 to operate the latch e, a pendent cord or chain being attached at its free end o, as shown. The bearing upper face, v, of the latch e is notched, so as to retain the elevator-frame in position, and a spiral spring, f, is attached to 80 the frame and the horizontal limb h, so as to retain the top face of the latching-bracket c in a horizontal position.

Upon the ceiling of the room or other stationary point above the rectangular frame R 85 of the upper track, P, a grooved pulley is fixed to support a chain or cord, g, the lower termination of which is affixed to the top of the cross-head b, the other being carried down a short distance and secured to the top end of 90 the dash-pot T. (See Fig. 1.) The dash-pot or air-cushion chamber T is preferably made cylindrical, with a valve, i, (see Fig. 8,) at its top. This valve should be made to rise when the body of the dash-pot is lowered. Any 95 suitable form of valve may be used; but for simplicity and effective action we prefer an ordinary flap-valve, as shown. The lower end of the cylindrical body is centrally perforated in its wall to receive the plunger-rod p. This 100 rod has a loose sliding fit where it reciprocates in the chamber T, so as to permit the gradual escape of air at this point. A plunger-head, p', is secured to the upper end of the rod p. The length of the rod p is made 105 sufficient to permit the cylinder to rise and fall its full length upon it without hindrance. The lower end of the rod p is secured by a proper base-flange to a bracket, i', and is preferably attached to the rear edge of the well-hole frame R of the upper track.

The track-section M, (see Figs. 3 and 4,) that forms a base-rail for the car of the cash-carrier when it is to be lowered at a station, is cut away or hollowed to afford room in its side 110 toward the track for the shifting-bar K to lie therein. This is a flat plate that is secured in place so as to have longitudinal movement a limited distance. Upon one of its ends, u, a spring, u', is mounted, this end of the bar K being rounded to receive the spring and permit it to work properly. The spring u' has an end abutment against the collar c', that encircles the rounded end u of the bar K. This collar c' has a rounded continuation, c'', that passes through 115 a longitudinal slot, c'', in the hollowed wall of track-section M, and is attached rigidly to the sliding bar K', that has a limited endwise sliding movement on anti-friction ferrules that are placed on the bodies of screw-studs s' s'', 120 which engage in longitudinal slots s' s'', made in the bar K. These studs s' s'' are firmly secured in the wall of track-section M. Upon the extension of the rod u, that projects a sufficient distance through the collar c' to permit 125 it, a spiral spring, u'', is mounted. This spring bears without compression on the free face of the collar c', and a perforated bracket, u', that 130 sustains the outer end of the rod u, affords a

bearing-surface for the other end of spring u^2 . (See Fig. 3.)

In Fig. 3 is shown the buffer-latch F. This is pivoted at a point, v' , on the shifting-bar K near the shoulder of the rounded extension u . Its vertical motion is controlled by a stud-bolt, v^3 , that is inserted in bar K and engages in an open slot, v^4 , formed on the end of the latch. A swinging recoil-arrester, t, is pivoted at t^2 . This piece is held from dropping too low by a projecting stud, t^1 . The free end of the recoil-arrester t is a proper distance from the vertical face l of the buffer-latch F to permit the abutment pin or projection on a car to lie between their opposite surfaces when it engages the latch F. An extension of the shifting-bar K to the right of the recoil-arrester t is also shown in Fig. 3. - This is serrated on its upper edge, and is engaged by a latch-dog, y^6 , that is the free end of a pivoted lever, the other end of which is held upward by a spring or the weight of the latch end y^6 . This device is similar to that shown in H. Thomas's application for patent on cash-carrier systems, filed August 27, 1886, Serial No. 212,016, and its office is to store the energy of the springs u u' when they are compressed by the momentum of a running car, so that when a car is elevated to an upper track to be dispatched to the cashier's desk the tripping of the lever is effected at the instant the elevator is in a line with this track, and there is thus given an impetus by the expended force of the released springs.

In Fig. 4 the slide-bar K' and its attached track-section M are shown in position on the lugs r , that are secured to the side of the well-hole frame I' of the lower track, U. The bar K' has a bearing pad, r^2 , attached at each end. These are adapted to rest upon the lugs r , and are of a proper length of face to permit them to pass freely through space-holes provided at the side of the frame I' by the right-angle bends or offsets given to the lugs r . By this method of construction of the lugs an endwise movement of the bar K' will dislodge it from its support on the lugs r , and allow it to fall clear of these bearing-points and below the track until arrested, as will be presently explained.

In order to prevent cars from distant stations running into the open well-hole upon the lower track at the instant that the car belonging to such a station is upon the elevator and has disengaged the elevator so as to open the track at this point and before the free track-section is in connection with the main track to close it, an arresting device is necessary.

We prefer to use a modification of a car-arrester that has been shown in the application of H. Thomas for cash-carrier systems, filed August 27, 1886.

In Fig. 5, at X^2 , is shown a gravity-bar that is pivoted at y . This fulcrum-point is so located as to make the weight of the bar somewhat greater toward the end V' . The portion of the bar toward the frame I' is bent at a right

angle, and at such a distance as will clear the attached offset end I^3 of the frame. The bar X^2 is again bent to extend parallel to the track U. At a point where the bar X^2 meets the frame I' it is bent to clear the side of the frame and project downwardly inside of it a short distance, and then again bend to extend horizontally to form a short portion, X^3 , that is a proper distance to the rear of the bar K' and parallel to it. From the rear side of the bar K' a pin, X^4 , is rigidly secured. This projects outward and parallel to the side of the frame I' a proper distance to lie upon the free end X^3 , and when the track-section M is in place will bear upon it, so as to hold the bent part y^3 of the bar X^2 firmly onto the top edge of the frame I'. The portion V of the bar X^2 is rounded to receive a spiral spring, s^6 , that is fastened by its end to the body of the rod V at Z. The rod is supported by a bracket-lug, s^5 , at its outer end, and passes through a perforation in the body of the bar X^2 at its inner extremity. (See Fig. 5.) The free end of the rod V is turned at a right angle, and forms a short downwardly-projecting toe, V'. This toe V' is of such a relative length as to be prevented from projecting below the lower surface of the main track upon which the bar X^2 is pivoted when the track-section M or the free track-section G is in position of alignment with the main track U.

When the elevator S is raised to dispatch a car, or at the instant it is lowering and before the free track-section G is in position in the main track U, this main lower track, U, is opened. When this occurs, the end V of the bar X^2 , by reason of its superior weight, will fall a short distance until the edge of the plate abuts and rests upon the check-pin Z, that is made to project from the frame U to stop it. This limited movement carries the toe V' down in the path of the abutment-pin on a running car, so as to collide with this, and so arrest the car before the gap in the track is reached. The momentum of the running car is absorbed by the elasticity of the yielding spring s^6 . When the track is again made continuous, the arrested car will be caused by the downward grade of the track to again resume a progressive movement toward its point of destination.

In Fig. 9 side and end views of a cash-carrier car are given, and it will be noticed that a pin or portion of the frame O' is made to project beneath the track, a clearance distance intervening between. This pin or projection O' is intended to engage the buffer-latch F on the track-section N, and by its action upon it operate the car-retaining device, as well as the mechanism for storing the force of car momentum, to be used to start a car upon the upper track, as has been previously explained.

The size of the dash-pot T is so proportioned that its body will be of a weight to slightly overbalance the cross-head, b, and latching-bracket c, so that when these parts are free from other connection the weight of the air-

chamber or dash-pot T will cause it to descend and the valve at its top to lift. The air being thus allowed to escape freely, the body will rest upon its plunger-head.

5 When a car runs upon the elevator that is in supported position in line with the lower track, its momentum will be communicated through the buffer F to the shifting-bar K. This will cause the bar K' to be dislodged off of the supporting-lugs, and the elevator S will fall and come in contact with the latching-bracket e on cross-head b, this being supported immediately below the lower edge of the elevator-frame S. The weight of the elevator will cause the air in the dash-pot T to be slowly expelled, and the elevator and car on it will sink gently till the air is entirely removed and the plunger-head p' be brought into contact with the lower head of the dash-pot T. The depression of the elevator and supported car can be further continued by pulling the chain or cord attached to the latch-limb h. This will lower the cross-head and also disconnect the latching-bracket e from the elevator, which 20 will run down the guides E till it reaches the hand of the clerk.

The depression of the elevator-frame S will replace the free track-section G in line with the tracks U, and thus permit the passage of 30 cars above the suspended elevator and car, as has been before mentioned.

When the contents of the carrier-car are removed and the car is hoisted, the rear side of the elevator-frame will impinge against the inclined edge of the latching-bracket e, and the same will yield, by action of the spring f, to 35 pass the elevator-frame, and then resume its normal position beneath the elevator.

Having fully described our invention, what 40 we claim as new, and desire to secure by Letters Patent, is—

1. In store-service apparatus, the combination of a cross-head and its guides with an air-cushion and means for connecting the cross-head and air-chamber, substantially as set forth.

2. In store-service apparatus, the combination, with an elevator-frame, its guides, and attached track-section, of a sliding cross-head, 50 its guides, an air-cushion chamber, and means for connecting the cross-head and chamber, substantially as set forth.

3. In store-service apparatus, the combination, with an elevator-frame, its guides, and 55 an attached track-section, and a cash-carrier car, of a sliding cross-head, its guides, an air-cushion chamber, and means of connecting the cross-head and air-chamber, substantially as set forth.

4. In store-service apparatus, the combination, with an elevator-frame, its guides, a supported free track-section, and an attached track-section, of a vertically-sliding cross-head, 60 its guides, an air-cushion chamber, and means for connecting the cross head and chamber, substantially as set forth.

5. In store-service apparatus, the combination, with an elevator-frame having an oscillating bracket, a supported free track-section, and an attached track-section, of a vertically-sliding cross-head, its guides, an air-cushion chamber, and a rope to connect the cross-head with the chamber, substantially as set forth. 70

6. In store-service apparatus, the combination, with an elevator-frame having an oscillating bracket, guides for the frame, a supported free track-section, an attached track-section, and a car or basket, of a vertically-sliding cross-head, its guides, an air-cushion chamber, and a cord to connect the cross-head 75 and chamber, substantially as set forth.

7. In store-service apparatus, the combination, with an elevator-frame having an oscillating bracket, guides for the frame, a supported free track-section, an attached track-section, buffer-plate and recoil-check on track-section, and a car or traveling basket, of a vertically-sliding cross-head, its guides, an air-cushion chamber, and cord to connect the cross-head and chamber, substantially as set forth. 80 90

8. In store-service apparatus, the combination, with an elevator-frame and its attached track-section, of a bar having sliding connection with the fixed track-section and a shifting-bar on front side of track-section adapted to 95 move longitudinally this sliding bar, substantially as set forth.

9. In store-service apparatus, the combination, with an elevator-frame, its guides, a free track-section, and a fixed track-section, of a 100 sliding bar that supports the elevator, two bracket-lugs that sustain the sliding bar, and a shifting-bar adapted to move endwise the sliding bar and drop the elevator off of its supporting-brackets, substantially as set forth. 105

10. In store-service apparatus, the combination, with an elevator-frame and its fixed track-section, of a bar that has sliding attachment to the fixed elevator-track section, the bracket-lugs that support the elevator in line with main track at a station, the shifting-bar, its buffer, latch, spiral springs, and collar between the springs that is secured by bolt projection to the slide-bar, ratchet-toothed edge of shifting-bar, and latching-lever that meshes into these serrations, substantially as set forth. 110 115

11. In store-service apparatus, the combination, with an elevator and its guides, the fixed track-section, its sliding bar, bracket-lugs, and shifting-bar, of an air-cushion chamber, a 120 sliding cross-head, its latching-bracket, and a means of connecting the air-chamber and cross-head, substantially as set forth.

In testimony whereof we have signed this specification in the presence of two subscribing witnesses. 125
